UNITED STATES PATENT OFFICE.

FRANZ A. FULLER, OF NEWARK, NEW JERSEY, ASSIGNOR TO THE J. E. MERCOTT COMPANY, OF NEWARK, NEW JERSEY, A CORPORATION OF DELAWARE.

BAG FASTENER.

Application filed December 3, 1920. Serial No. 427,945.

To all whom it may concern:

Be it known that I, FRANZ A. FULLER, a citizen of the United States, residing in Newark, in the county of Essex and State of New Jersey, have invented certain new and useful Improvements in Bag Fasteners, of which the following is a specification.

This invention has as its main object to provide a bag fastener whereby the two metal side frames of the bag may be either temporarily secured in engagement by spring actuated bolt devices readily released by hand, or positively locked in such manner as to require a key in order to separate the same in obtaining access to the bag.

A further object is to provide a neat and attractive type of bag fastener comprised of few and simple parts, cheaply constructed and readily applied.

These and other analogous objects are attained by the novel construction, combination and arrangements of parts herein-after described and shown in the accompanying drawings forming a material part 25 of this disclosure, and in which:—

Figure 1 is a fragmentary side elevational view of a conventional type of bag showing a fastener made in accordance with the invention in operative position.

Figure 2 is an enlarged longitudinal sectional view of the fastener, showing in broken lines its position when moved to release the frame sides.

Figure 3 is a side elevational view of the same.

Figure 4 is a longitudinal sectional view taken on line 4—4 of Figure 2.

Figure 5 is a transverse sectional view taken on line 5—5 of Figure 3.

Figure 6 is a perspective view of the locking post.

Figure 7 is a top plan view of the hooked plate member.

Referring to the drawings in detail the numeral 10 designates a fragmentary portion of the bag material, 11 a fractional part of the front frame and 12 the corresponding portion of the rear frame.

Riveted to the outside of the front frame, 50 is a plate 15, provided with a normally pendent pivoted pull 16 and having a pair of angularly bent catches 17 containing open transverse slots 18 engageable with the sliding element of the fastener in the usual manner.

A hollow casing comprised of a top plate 20, straight parallel side walls 21, and curved ends 22 having extending lugs 23, is secured upon the upper surface of the frame element 12, by the lugs 23, which are turned inwardly when assembling, passing through openings in the frame and acting as rigid clamps holding the casing firmly in position in register with the plate 15, the catches 17 being enterable into the casing through openings 24 formed in its front wall.

Formed through the plate 20, adjacent the side walls, are two pairs of narrow parallel slots 25 and 25', the latter having centrally between them a sheared clip or prong 26, while central in the length of the plate is a relatively large opening 27 having a cam-like profile, its opposite sides being of a different radius, its ends substantially straight and parallel and the profile adjacent the unbroken side extended below the end towards the slots 25 forming a recess 28, the purposes of these several slots, lugs and openings being further on explained.

A cap piece 30 also hollow and smaller in length and width is slidably mounted on the casing, this cap having a transversely curved top except at its raised flat center 31 which has an expanded central socket 32.

Soldered or otherwise secured within the cap is reinforcement 34 shaped in conformity and having opposed pairs of extending undercut lugs 33 adapted to project through the slots 25 and be bent slightly inward towards each other over a plate 35 disposed against the inner surface of the plate 20 conveying lineal motion to the same and at the same time slidably securing the cap and plate 35 to the casing.

The plate 35 is formed with raised angularly turned edges 36 and 36' serving as guides within the side walls of the casing, the side 36 having cuts 37 adapted to engage the slots in the catches 17 and maintain them in a locked position.

Formed in the plate 35 are two raised elements 38 adapted to reduce the area in frictional contact with the plate 20 and midway in its length, to one side of the center is a single raised stop 39 adapted to make contact with the ends of the openings 27 and 28, limiting the relative sliding movement between the plates 20 and 35.

A post or stud 40 extends slightly above the cap element 31, through which, together with the reenforcement 34, it passes.

The upper end of the post contains an axial bore 41 and a cross slot 42, the former being receptive of the point 43 of the key 45, the broadened portion 44 of which engages the slot 41 while the nibs 46 prevent the key from entering an undesirable depth.

At the inner end of the post is a flange 48, between which and the plate 34 is a compression spring 49 encircling the post, tending to press the flange 48 towards the plate 20.

Formed on the outer surface of the flange is a rectangular lug 50 having straight parallel sides extending from the center to the periphery of the flange in alignment with the slot 41.

Extending from the lug axially of the post, is a pivot 51, the same passing through a guide opening appropriately formed in the plate 35.

Another compression spring 52 is disposed within the cap, extending from one end to the prong 26 by which it is maintained in operative position, this spring acting to press the cap into engagement with the stop 39 causing the cap and casing to normally register but permitting the cap to be moved at such times as the lug 50 is turned into the position shown in Figure 2.

When it is desired to lock the bag, the key is inserted and the post rotated, bringing the lug into the position shown in Figure 3, this turning of the post causing the lug 50 to rise as it passes over the top of the stop 39, against the spring 49, the opening 27 permitting the lug to be turned forward or back through 180 degrees only.

Obviously when the parts are in the position shown in Figure 3, that is the outer end of the lug 50 being in contact with the straight wall of the opening 27, at its left hand end as illustrated, the cap and parts carried by it cannot be moved lengthwise of the casing into the position shown by the broken lines in Figure 2 and the bag is effectively locked against intrusion.

It will be equally apparent that when the position of the lug is reversed the parts can be moved against the force of the spring 52, permitting the catches 17 to be withdrawn from engagement with the sliding bolt elements carried by the plate 35 and access had to the bag.

From the foregoing it will be seen that a neat and effective bag fastener has been disclosed capable of fulfilling its several objects.

However the foregoing disclosure is to be regarded as descriptive and illustrative only, and not as restrictive or limitative of the invention, of which obviously an embodiment may be constructed including

many minor modifications without departing from the general scope herein indicated and denoted in the appended claims.

Having thus described my invention, what I desire to secure by Letters Patent is:—

1. A bag frame fastener comprising an elongated casing provided with an internal cam in the top wall thereof fixed to one of the frames, a bolt element slidable therein, means in said casing for normally projecting the bolt in one direction, a catch carried by the other of said frames, said catch being engageable with said bolt, and key operated means engageable with said internal cam in said casing adapted to confine said bolt, 70 when in one position and to release the bolt when in another position.

2. A bag frame fastener comprising a fixed elongated casing, a hollow element slidably mounted thereon, a catch enterable 85 into said casing, means on said slidably element engageable with said catch, means in said slidably element normally causing its engagement with said catch, an internal cam in the top wall of said casing, a key operated post journalled in said slidably element, an offset lug on said post operable in said cam, and means for resiliently maintaining said post in either of two adjusted positions, said lug when in one position preventing the 95 movement of said slidably element and permitting it to release said catch when in another position.

3. The combination in a bag fastener 100 comprised of engaging elements fixed respectively on the frames of a bag, one of said elements carrying a longitudinal slide having means for engaging the other element, of a post rotatably mounted in the sliding member, said post having an opening receptive of a key whereby it may be rotated, a plate slidable in the element carrying the slide, said plate being moved thereby, an internal cam in said element above said plate, an offset lug on said post operable in 105 said cam, said cam limiting the movement of said lug, a stop on said plate engageable by said lug over which the lug rides when rotated, means for pressing said post towards said plate and means carried by said 110 plate engageable with the other of said fixed elements.

4. In a bag frame fastener, the combination with a casing provided with an internal cam in the top wall thereof fixed on one 115 frame, a slide on said casing and a catch carried by the other frame, of a plate in said casing slidably secured to said slide and having means for engaging said catch, a spring in said slide operating to retract it 120 when extended, a key operated post rotatable in said slide and plate, a flange on said post, a compression spring encircling said post for maintaining it in operative position, a lug on said post extending from the 125

center to its edge, said lug being operable in an opening in said casing having an internal cam profile and a stop formed with said plate adapted to retain said lug in either of two adjusted positions, said stop being movable longitudinally in the mentioned cam opening.

This specification signed and witnessed this 29th day of November, 1920.

FRANZ A. FULLER.
